BOW SIGHT

Donald Jacobson, B 1, and Isaac Davis, 915 4th St. S.,
both of St. James, Minn.
Filed Aug. 9, 1960, Ser. No. 48,448
2 Claims. (Cl. 33—46)

This invention relates to a sighting device, and more particularly to a sight for an archer's bow.

The object of the invention is to provide a bow sight which can be readily and conveniently adjusted, and wherein after the parts have been adjusted to the desired location, accidental shifting or movement thereof will be prevented.

Another object of the invention is to provide a bow sight which will accommodate different types of sights such as a tapered hooded post sight, a prism, a cross bar or the like, and wherein the hooded sight is adapted to be tapered to prevent shadows and glare from adversely affecting the pin sight.

Another object of the invention is to provide a bow sight which has a means for accomplishing a fine adjustment thereof so that for example windage can be compensated for, and wherein suitable scale markings are provided for indicating yardage and adjustment, the bow sight being constructed so that slippage is prevented and wherein the user will be able to use the device with increased speed and accuracy.

A further object of the invention is to provide a bow sight which is extremely simple and inexpensive to manufacture.

Other objects and advantages will be apparent during the course of the following description.

In the accompanying drawings, forming a part of this application, and in which like numerals are used to designate like parts throughout the same:

FIGURE 1 is a front elevational view of the bow sight, constructed according to the present invention.

FIGURE 2 is a sectional view taken on the line 2—2 of FIGURE 1.

FIGURE 3 is an end elevational view of the bow sight, with portions of the bow broken away and in section.

FIGURE 4 is an elevational view of the spring member.

FIGURE 5 is a sectional view taken through the bow sight of the present invention.

FIGURE 6 is a side elevational view showing the sighting device of the present invention mounted on a bow.

Referring in detail to the drawings, the numeral 10 indicates a conventional bow which includes the intermediate portion 11, FIGURE 6, and the numeral 12 indicates a portion of an arrow which is adapted to be engaged by the usual string 13 of the bow 10.

According to the present invention there is provided a bow sight which is indicated generally by the numeral 14, and the bow sight 14 includes an elongated bar 15 that comprises a main body portion 16 of rectangular flat configuration, and scale markings or indicia 17 are ranged along the longitudinal side edges of the main body portion 16. The numerals 18 and 21 indicate upper and lower end portions of reduced size, and the upper portion 18 is longer than the lower portion 21, and these portions are provided with apertures or openings 19 and 22 respectively whereby suitable securing elements such as screws 20 can be extended through these apertures and into engagement with the bow 10 in order to fasten the sight 14 in place on the bow.

As shown in the drawings a tape 23 is adapted to extend longitudinally along the outer or upper surface of the main body portion 16 and the tape 23 may be secured to the bar in any suitable manner as for ex-

2

ample by means of a suitable adhesive, and this tape 23 is provided with markings such as the markings 24 thereon.

The numeral 25 indicates a block which is adjustably connected to the bar 15 for sliding movement therealong, and the block 25 includes side portions 26 as well spaced apart flanges 27, and the numeral 28 indicates the space between the flanges 27. The block 25 is provided with a slot or opening 30 therein through which 10 extends the bar 15. The numeral 29 indicates a recess in a shoulder 31 on the block 25, and the recess 29 provides clearance space for the tape 23.

The numeral 32 indicates a spring member which includes a major section 33 which extends through the slot 30, and the spring member 32 further includes end portions 34 and 35 which are arranged as shown in FIGURE 4.

The numeral 37 indicates a locking screw which is adapted to extend through one of the spaced apart 20 threaded openings 36 in the block 25, and the inner end of the locking screw is adapted to engage the spring member 32 as later described in this application.

As shown in the drawings, there is provided an adjustable substantially U-shaped support member which is indicated generally by the numeral 38, and the support member 38 includes a pair of spaced apart legs or stems 39 and 40. The stems 39 and 40 traverse bores in the block 25 so that the support member 38 is mounted on the block 25 for sliding back and forth movement transversely of the bar 15. The stem 39 is threaded externally, while the stem 40 is smooth, and the support member 38 further includes a bight or arcuate section 41, FIGURE 1. The numeral 42 indicates a tapered sight which is adapted to be mounted in or connected to the arcuate section 41 in any suitable manner, and a pin sight 43 may be suitably affixed to the tapered sight 42.

The shoulder or enlargement 31 comprises a pair of spaced apart protuberances or projections 44 which are shaped to define or provide a space or chamber 45 therebetween, and the numeral 46 indicates a knurled actuator or nut which abuttingly engages the walls of the chamber 45 and threadedly engages the stem 39, as shown in the drawings.

The numeral 47 indicates a lock means embodying a screw member which engages a threaded opening in the shoulder 31 and the inner end of the screw member 47 is adapted to engage the stem 40 so as to maintain or lock the support member 38 in its various adjusted positions.

From the foregoing, it is apparent that there has been provided a bow sight, and with the parts arranged as shown in the drawings, it will be seen that the sight 14 is adapted to be attached to a bow such as the bow 10, and the sight 14 is adapted to be secured in place by means of suitable securing elements such as the screws 20 which extend through the apertures 19 and into engagement with a portion such as the intermediate portion 11 of the bow 10. The sight 14 includes a bar 15 which has the main body portion 16 of rectangular configuration and there is provided a scale marking 17 along the longitudinal edges thereof. The block 25 is adjustably mounted on the bar 15, and by loosening the screw 37, the block 25 and its associated parts can be moved up or down on the bar 15, and after the block has been moved to the desired location, the screw 37 is tightened in order to maintain the block 25 immobile in its desired position.

In addition, by loosening the set screw 47 so that the inner end of the set screw 47 is out of engagement with the stem 40 of the support member 38, the actuator 46

can be manually turned, and since the actuator 46 is arranged in threaded engagement with the stem 39, it will be seen that the support member 38 can be moved in or out with respect to the block 25 as the actuator 46 is rotated, and since a sight such as the sight 42 is mounted in the arcuate section 41 of the support member 38, it will be seen that this manual rotation of the actuator 46 will permit the sight 42 to be arranged at the desired location. The pin sight 43 is suitably affixed to the sight 42 whereby this member can be arranged at the desired location in order to insure that the user can sight therethrough whereby the arrow 12 can be shot with increased accuracy. After the member 38 has been moved to the desired location, by means of the actuator 46, the set screw 47 is adapted to be tightened in order to prevent accidental shifting or movement of the support member 38.

The parts can be made of any suitable material and in different shapes or sizes.

The bow sight of the present invention has certain important advantages or features which are not found in prior similar devices. For example the bar 15 is adapted to be made of a suitable material such as aluminum and is adapted to be finished in chrome so as to prevent glare and this permits writing or markings thereon. The upper end 18 is longer than the lower end 21 for easier fastening to the bow. The graduation marks or indicia 17 on the bar are arranged so that every third marker is longer and this permits the user to more easily tell when the block is moved. The machined block 25 makes it possible to put in a marking tape such as the tape 23. The overall length of the bar may be seven and five-eighths inches, one-half inch wide and one-eighth of an inch thick.

In addition, the sight block is adapted to be made of aluminum and has the buffer spring 32 which serves to hold the sight block from slipping when the locking screw 37 is loosened for sighting or adjustment of the device. The windage adjustment includes the screw type setting and locking nut, that is it includes the actuator 46 as well as the locking member 47 and the member 47 serves to hold the support member in a fixed position after setting. The buffer spring 32 can be used on either side for right or left hand users. The tightening screw 37 when tightened against the buffer spring 32 locks the block 25 in place. The threaded holes 36 are arranged in all four corners of the block so that the user has an optional arrangement or choice as to where the tightening screw 37 is to be located.

In addition as shown in FIGURE 5 for example, the block 25 is recessed as at 29 so that a tape such as a quarter-inch tape can be used for marking if one desires to use the tape.

The wireloop 41 permits the use of either a tapered hooded post sight such as the sight 42, or else a prism, or a cross bar can be used as the user desires. The hooded sight such as the sight 42 is tapered so as to keep shadows and glare on the pin sight 43 to a minimum.

As previously stated, one stem 39 of the wire loop or support member 38 is threaded for fine adjustment sideways for windage by the use of the three-eighths inch diameter knurled nut or actuator 46 and this is an important aspect or feature of the bow sight of the present invention. The knurled stem screw 47 tightens down on the stem 40.

The markings such as the markings 17 and 24 indicate yardage and adjustment can be made to permit the arrow to be fired or shot accurately and readily. The

various tightening screws insure that accidental slippage will be prevented or minimized, and also speed and accuracy for the user will be insured.

The space 28 between the flanges 27 may be approximately three-eighths of an inch in size, that is the distance between the flanges 27 may be three-eighths of an inch, but this dimension may vary as desired.

The end portion 18 is longer than the portion 21 for the purpose of applying tape to the bow so that the sight can be aligned before screwing into the bow.

As shown in FIGURE 4 for example, the ends of the spring 32 are shaped as at 34 and 35 and a portion such as the portion 35 prevents the spring from accidentally falling out of its proper location or position.

Minor changes in shape, size and rearrangement of details coming within the field of invention claimed may be resorted to in actual practice, if desired.

What is claimed is:

1. In a bow sight including an elongated bar adapted for attachment to a bow, calibration indicia carried by the bar, a block mounted on the bar for sliding movement therealong and means for selectively positioning said block on said bar, a sight support member of substantially U-shaped configuration having its legs mounted in said block for sliding movement transversely of said bar, the bight of said member being adapted to detachably hold a sight element, one of the legs of said support member being threaded, and a knurled nut on the threaded leg engaging said block and operable when rotated to move said member relative to said block.

2. In a bow sight including an elongated bar adapted for attachment to a bow, calibration indicia carried by the bar, a block mounted on the bar for sliding movement therealong, and means for selectively positioning said block on said bar, a sight support element of substantially U-shaped configuration having its legs mounted in said block for sliding movement transversely of said bar, the bight of said member being adapted to detachably hold a sight element, one of the legs of said support member being threaded, a knurled nut on the threaded leg engaging said block and operable when rotated to move said member relative to said block, and lock means carried by said block engageable with the other leg of said member for releasably holding said member in any position of its adjusted movement.
